US00D856323S

(12) **United States Design Patent** (10) Patent No.: **US D856,323 S**
Wall et al. (45) Date of Patent: **** Aug. 13, 2019**

(54) **ELECTRONIC DEVICE**

- (71) Applicant: **Amazon Technologies, Inc.**, Seattle, WA (US)
- (72) Inventors: **Timothy Eli Wall**, Sausalito, CA (US); **Christopher Green**, San Francisco, CA (US); **Wilfrido Loor Canizares**, San Francisco, CA (US)
- (73) Assignee: **Amazon Technologies, Inc.**, Seattle, WA (US)
- (**) Term: **15 Years**
- (21) Appl. No.: **29/654,954**
- (22) Filed: **Jun. 28, 2018**

Related U.S. Application Data

- (63) Continuation of application No. 29/594,346, filed on Feb. 17, 2017, now Pat. No. Des. 824,383, which is a continuation of application No. 29/542,764, filed on Oct. 16, 2015, now Pat. No. Des. 779,483.

CLAIM

The ornamental design for an electronic device, as shown and described.

DESCRIPTION

FIG. 1 is a first perspective view of an electronic device, taken from the front;

FIG. 2 is a second perspective view of the electronic device, taken from the back;

FIG. 3 is a front view of the electronic device;

FIG. 4 is a back view of the electronic device;

FIG. 5 is a right-side view of the electronic device;

FIG. 6 is a left-side view of the electronic device;

FIG. 7 is a top view of the electronic device; and,

FIG. 8 is a bottom view of the electronic device.

The dashed broken lines in the drawings depict portions of the electronic device which form no part of the claimed design. The dot-dashed broken lines represent boundaries of the claimed electronic device and form no part of the claimed design.

1 Claim, 6 Drawing Sheets
